CAN OPENER

Thomas W. Costello, Everett, Wash.

Application February 5, 1947, Serial No. 726,668

1 Claim. (Cl. 30—8)

1

This invention relates to a can opener, and more particularly to the type of opener that cuts the top out of a can.

The primary object of the invention is to effect a clean, smooth cut through the top or end closure of an ordinary type food container without leaving slivers of metal or rough edges which are liable to injure the user.

Another object is to easily and quickly cut the top completely out of the ordinary type of food-containing can.

The above and other objects may be attained by employing this invention which embodies among its features a wall bracket, a holder adapted to be removably attached to the wall bracket, a cutter at the upper edge of the holder, a traction wheel adapted to advance a can into cutting engagement with the cutter, a hand crank for rotating the traction wheel, means to positively advance the traction wheel toward the cutter during its initial rotation, and means to sustain the traction wheel in such advanced position, but out of engagement with the initial advancing means while the wheel is being rotated to complete the cutting of the top out of the can.

In the drawings,

Figure 1 is a side view in elevation of a can opener embodying the features of this invention.

Figure 2 is a vertical sectional view taken substantially on the line 2—2 of Figure 1.

Figure 3 is a view similar to Figure 2 looking in the direction of the arrows 3—3 in Figure 1.

Figure 4 is a horizontal sectional view taken substantially on the line 4—4 of Figure 3.

Figure 5 is a fragmentary side view of the holder and cutter, showing the traction wheel-advancing means as being formed separately from the holder.

Figure 6 is a transverse sectional view taken substantially on the line 6—6 of Figure 5.

Referring to the drawings in detail, a wall plate 10 which is of substantially rectangular shape is provided adjacent its four corners with openings for the reception of screws 11 by which the plate is adapted to be attached to a wall or other vertically extending support. This wall plate is provided with oppositely extending U-shaped incisions 12 forming tongues 13 which are adapted to be bent outwardly and overlie attaching flanges on the holder or bracket to be more fully hereinafter described. Somewhat similar U-shaped incisions 14 are arranged in opposed relation to the incisions 12 and these last incisions define tongues 15 which are adapted to be bent outwardly to form side guides for engage-

2

ment with the side edges of the brackets previously referred to.

The bracket previously referred to is designated generally 16 and comprises a shank member 17 having formed at its rear edge laterally extending tongues 18 which are adapted to be removably engaged with the plate 10 beneath the tongues 13 and between the tongues 15 thereon. It will thus be seen that the bracket 16 will be held in a vertical position. Formed at the end of the shank 17 opposite that carrying the tongues 18 is a head 20 which is substantially square in plan and carries at its upper end a projection 21 which extends upwardly and is bent back upon itself, as at 22, to form a depending cutter member 23, the lower edge 24 of which is sharpened and inclined, as shown in Figure 1, to form a cutter by which the top of a can which is pressed into contact therewith may be easily and quickly severed from the can. Formed in the head 20 in vertical alignment with the longitudinal axis of the extension 21 and blade 24 is a vertically extending slot 25 into the upper end of which opens a slot 26 which extends horizontally so that the two slots form a substantially inverted L-shaped slot in which the axle shaft of the traction wheel to be more fully hereinafter described is adapted to ride. Formed in the head 20 and extending toward the shank 17 is a pair of spaced incisions 27 which are joined with a group of zig-zag incisions 28 formed in the head 20 to produce a tongue 29 having an arcuate row of teeth 30 formed in the end thereof. This tongue 29 is bent outwardly, as illustrated in Figure 2, so that the teeth 30 which project toward the slot 25 lie in a plane different from that of the general plane of the head 20.

It is apparent that should it be so desired, the tongue 29 may be replaced by a plate 29a which may be riveted as at 29b to the side of the head 20 and that the plate 29a may be formed with an arcuate row of teeth 30a as shown in Figure 5.

Extending through the slot 25 or 26 is an axle shaft 31 carrying adjacent one end of a crank arm 32 having a crank handle 33 at its extreme end, and on the opposite side of the head 20 the axle shaft 31 has fixed thereto a traction wheel 34, the peripheral edge of which is serrated, as at 35, and when the wheel is advanced toward the cutter 23, the serrated edge rides in alignment with the space between the cutter and the head, as will be appreciated from reference to Figure 2. It will be noted upon reference to Figure 1 that the teeth 30 on the tongue 29 engage the peripheral serrations 35 of the wheel 34 when the axis

of the axle shaft 31 aligns with the longitudinal axis of the slot 25, but when the axle shaft moves upwardly and then transversely into the slot 26, the serrations 35 of the wheel 34 will be moved out of engagement with the teeth 30 so that the wheel may be freely rotated.

In operation, when it is desired to open a can, the outer crimped edge of the upper end of a can is placed between the serrated periphery of the wheel 34 and the lower edge 24 of the cutter 23, it being assumed that the axle shaft 31 is in its lowermost position in the slot 25. Upon rotating the axle shaft and wheel 34 by means of the handle 33, the teeth 30 engaging the peripheral teeth 35 of the wheel 34 will cause the wheel to positively move upwardly, carrying the can with it so as to force the end closure of the can against the sharpened edge 24 of the cutter 23. Upon continued motion of the wheel, the frictional contact of the periphery thereof against the bead at the upper end of the can will cause the axle shaft 31 to move into the horizontal slot 26 so that upon further movement of the crank 33 the wheel will clear the teeth 30 and may be continuously operated until the upper end of the can has been rotated 360° around the periphery thereof with the cutter 23 cutting the entire top out of the can in this manner. Upon reversing the motion of the wheel 34, the axle shaft 31 will be returned to its former position at the upper end of the slot 25, which will cause the serrations 35 of the wheel 34 to mesh with the teeth 30 on the rack tongue 29 and thus retract the wheel and restore it to position to repeat the operation. Such retraction of the wheel will facilitate the removal of the opened can from contact with the cutter 23 and the device is then

ready for a repetition of the operation just outlined.

While in the foregoing there has been shown and described the preferred embodiment of this invention, it is to be understood that minor changes in the details of construction, combination and arrangement of parts may be resorted to without departing from the spirit and scope of the invention as claimed.

10 I claim:

A can opener comprising a holder, a stationary cutter carried by the upper edge of the holder, said holder having a vertical slot in axial alignment with the vertical axis of the cutter and also having a horizontal slot opening into the upper end of the vertical slot, an axle shaft rotatable in the slots, a traction wheel carried by the axle shaft, an annular series of peripheral teeth on the wheel adapted to engage a cam and rotate it against the cutter, and a stationary rack carried by the holder and adapted when the axle shaft is in the vertical slot to engage the teeth on the wheel and advance the traction wheel toward the cutter as the axle shaft is rotated in one direction.
